UNITED STATES PATENT OFFICE

GERARDO F. MARCIANO, OF PROVIDENCE, RHODE ISLAND, ASSIGNOR TO UNIVERSAL OPTICAL CORPORATION, OF PROVIDENCE, RHODE ISLAND, A CORPORATION OF RHODE ISLAND

OPHTHALMIC MOUNTING

Application filed October 1, 1928. Serial No. 309,596.

This invention relates to an improved construction of ophthalmic mounting; and has for its object to provide in such a mounting a bridge member formed in substantially **U**-shape having a cross bar with elongated, downwardly-extending side arms curved to conform to the contour of the inner surface of the eyewires and attached to the eyewires.

A further object of the invention is to extend the side arms down to a point adjacent a medial line thru the eyewires and each arm having a tubular rivet or other fastening by which it is secured to its eyewire.

With these and other objects in view, the invention consists of certain novel features of construction, as will be more fully described, and particularly pointed out in the appended claims.

In the accompanying drawings:

20 Fig. 1 is a front elevation partly in section illustrating my improved bridge member as connecting together two spaced non-metallic eyewires.

Fig. 2 is an edge view of the construction illustrated in Fig. 1.

Fig. 3 shows the bridge member as detached from the eyewires and illustrating the tubular rivets as connected to the side arms of the bridge.

30 Fig. 4 illustrates a length of tubular wire which is to be cut into short lengths and the lengths being secured at one end to the side arms of the bridge member to serve as attaching rivets.

35 Fig. 5 is a fragmental view partly in section illustrating tubular rivets on an arm of the bridge member as extending thru the stock of the eyewires and upset on its inner surface to rivet the arm to the eyewires, the rivets being widely spaced and located at the opposite ends of the side arm.

Fig. 6 shows the lower rivet on the side arm as being located on the medial line thru the eyewires.

45 Fig. 7 is a view showing the two rivets on the side arm as straddling the medial line thru the eyewires.

It is found in the practical construction of ophthalmic mountings, of advantage in some instances, to form the bridge member

with a cross bar located a substantial distance above the medial line thru the lenses and adjacent a line across the upper edges of the eyewires and provided with elongated downwardly-extending and inwardly-curved side arms arranged to set against the inner edges of the eyewires and to provide these side arms each with one or more rivets by which these side arms may be secured to the eyewires, the rivets being preferably formed of tubular wire soldered at one end to the bridge arm and arranged to extend thru the eyewires and be upset or spread at its inner end to rivet the bridge to the eyewires; and the following is a detailed description of the present embodiment of my invention and showing means by which these advantageous results may be accomplished:

With reference to the drawings, 10 designates the eyewires which in this particular case are shown as being formed of non-metallic material, and 11 designates the bridge member which comprises across bar 12, the upper portion of which is herein shown as being substantially on an imaginary line extending between the upper edges of the eyewires.

This cross bar is provided with a pair of downwardly-extending side arms 13, each of extended length, and inwardly curved to follow the contour of the inner edge of its wire and to set in contact therewith. In order to fasten the side arms of this bridge member securely to its eyewires, I have soldered short lengths of tubular wire 14, best illustrated in Fig. 3, to extend laterally from these side arms and have provided corresponding openings 15 in the eyewires thru which these tubular rivets 14 may extend.

The inner ends of these rivets are spread against the inner surface of the eyewires to bind and fasten the side arms onto the eyewires.

Inasmuch as this type of bridge member is not intended or shaped to rest upon the nose of the wearer, I have secured a pair of nose guards 16 to these side arms preferably on a medial line thru the lenses, each of the guards being provided with a bendable arm 17 which is secured to its side arm of the bridge mem-

ber preferably at a point adjacent the medial line thru the eyewires.

In some instances, these side arms 13 may extend down to a point adjacent the medial line, as illustrated in Figs. 1, 5 and 6, in which case both of the rivets are shown as being above this medial line, while in other instances, as best illustrated in Fig. 7, the lower end 18 of the bridge arm is extended to a point a substantial distance below this medial line and the rivets 19 as being arranged to straddle this medial line, but any desired arrangement of positioning these rivets or fastening members relative to the medial line, may be employed.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. An ophthalmic mounting comprising a pair of spaced non-metallic eyewires, a bridge member having a cross bar with spaced elongated downwardly-extending side arms in the plane of said eyewires and closely fitting against the inner edges of the eye-wires, and attaching means on each arm secured to the edge thereof contiguous to the eyewire and projecting from each of said arms in the plane of said arms and extending from said eyewires for binding and securing each arm to its eyewire.

2. An ophthalmic mounting comprising a pair of spaced eyewires, a bridge member having a cross bar with spaced elongated downwardly-extending side arms in the plane of said eyewires closely fitting against and curved to follow the contour of the eyewire and spaced rivets secured to and projecting from the inner surface of each arm in the plane of said arms and eyewires and extending through said eyewires, and a nose guard attached to each of said arms.

3. An ophthalmic mounting comprising a pair of spaced eyewires, a bridge member having a cross bar set substantially on a line with the upper edge of the eyewires and having elongated downwardly-extending side arms in the plane of the eyewires and closely fitting the curvature of the inner edges of the eyewires, said side arms having tubular rivets projecting therefrom and in the plane of the arms and eyewires extending through the eyewires and upset on the inner surface thereof, and nose guards attached to said arms adjacent the medial line through the eyewires.

4. An ophthalmic mounting comprising a pair of spaced eyewires, a bridge member having a cross bar set substantially on a line with the upper edge of the eyewires and having downwardly-extended side arms in the plane of the eyewires resting against and fol-

lowing the contour of the inner edge of the eyewires to a point adjacent the medial line through the eyewires, a pair of spaced fastening rivets projecting from the edge of each side arm in the plane of the arms and eyewires to extend through the eyewire and be upset on its inner surface one of said rivets being adjacent the lower end of said arm, and a nose guard attached to each arm.

5. An ophthalmic mounting comprising a pair of spaced eyewires, a bridge member having a cross bar with spaced elongated downwardly-extending side arms in the plane of said eyewires curved to follow the contour of the eyewire and spaced rivets projecting from the inner surface thereof and in the plane of the arms, and a nose guard attached to each of said arms.

In testimony whereof I affix my signature.

GERARDO F. MARCIANO.
